United States Patent

Des. 235,931
Patented July 15, 1975

235,931

INFANT FEEDING BOTTLE

Paul Kenneth Meeker, Kent, Ohio, assignor to
Questor Corporation, Toledo, Ohio

Filed Oct. 16, 1974, Ser. No. 515,346

Term of patent 14 years

Int. Cl. D7—01

U.S. Cl. D83—8 A

FIG. 1

FIG. 2

FIG. 3

FIG. 4

FIG. 5

FIG. 6

FIG. 1 is a front elevation of an infant feeding bottle showing my new design;

FIG. 2 is a right side elevation thereof;

FIG. 3 is a left side elevation thereof;

FIG. 4 is a rear elevation thereof;

FIG. 5 is a top plan view thereof; and

FIG. 6 is a bottom plan view thereof.

We claim:

The ornamental design for an infant feeding bottle, as shown.
